UNITED STATES PATENT OFFICE.

NICHOLAS MARIE, OF PEORIA, ILLINOIS.

SACK-HOLDING DEVICE.

1,090,160.

Specification of Letters Patent. Patented Mar. 17, 1914.

Application filed June 25, 1912. Serial No. 705,883.

To all whom it may concern:

Be it known that I, NICHOLAS MARIE, citizen of the United States, residing at Peoria, in the county of Peoria and State 5 of Illinois, have invented certain new and useful Improvements in Sack-Holding Devices; and I do hereby declare that the following is a full, clear, and exact description of the invention, which will enable others 10 skilled in the art to which it appertains to make and use the same.

This invention pertains to a sack holding device.

It relates particularly to a device for use 15 in mills, feed stores and the like for holding open the mouth of a sack so that said sack may be readily filled.

It relates, also, to a device for supporting and holding open the mouth of a sack.

20 The object of the invention is to provide a simple means for holding open the mouth of a sack and for releasing said sack when filled, together with means for automatically returning the first said means to its 25 original position for receiving another sack.

To the end that the invention may be understood I have provided the accompanying drawing, in which:

Figure 1 is a side elevation of my sack 30 holding device. Fig. 2 is a front elevation of the same. Fig. 3 shows a portion of the device in perspective. Fig. 4 shows the device in plan. Fig. 5 is an elevation of a spike and a holding device for the same. 35 Fig. 6 shows a bell-crank-lever in perspective, and Fig. 7 is a cross section of one of the supporting bars of the frame of the device showing the spike in Fig. 5 in connection therewith.

40 C C are two uprights or frame members as the supporting parts of the sack holding device which for convenience may be mounted upon a suitable support, in this instance and merely for illustration the platform of 45 a weighing scale A by means of members D for example. The vertical extension of said member D is secured to the member C by means of bolts F for example, it being understood, of course, that one of these 50 members is provided for each said upright C.

At the top of each upright C and secured thereto near one end is a horizontally disposed bar G so placed as to extend forward to overhang the member upon which

the members C are mounted. A diagonally disposed brace H is secured at its ends to said bars G and the uprights C as clearly shown, so as to lend stiffness and strength to the structure. As an additional strengthening 60 means, and as a support also for parts to be described presently, plates J are secured to the inner sides of the members G and the said uprights.

Extending through the rear ends of the 65 bars G is a bolt K, Fig. 3, upon which is carried a piece of tubing L for spacing the two bars G apart. Below the bolt K and extending through the plates J just described is a rock shaft M preferably threaded 70 at its ends to receive a pair of nuts N O shown in Fig. 3, there being but one of the sets of nuts shown. Placed upon the shaft between the two nuts N O is a bell-crank-lever P constructed for instance of sheet 75 metal, or it may be a casting. As shown in Fig. 6, one corner of the lever is provided, for convenience, and as a good means of fixing the lever relative to the rock-shaft, with an ear Q at two of its edges which are 80 bent over into planes perpendicular to the plane of the lever to engage the sides of the nut N, as shown in said Fig. 3. The two nuts are adjusted on the threads to clamp the lever firmly between them and as to lock 85 one another so that they cannot loosen.

The lower corner of the lever, as arranged in Fig. 3, has pivoted thereto one end of a rod R whose other end is pivoted to the lower corner of a lever S at the front of the 90 device which lever is pivoted in any good manner to the plate J and is provided with a handle T. It is understood that substantially the same structure is provided at the other side of the apparatus, see Fig. 2. 95 Immediately above the forward free ends of the levers P and S the bars G are provided with vertical bores U each of which is preferably fitted with a tube V, Fig. 7. Slidable in each tube is a spike W whose 100 lower end is suitably carried in any form of fitting pivotally attached to the said levers P S. I have indicated in Fig. 5, as one of the means of carrying these spikes, a sheet metal member 2. This takes the general 105 form shown in Fig. 3 being provided in its top with a hole 3, Fig. 5, through which the spike extends. In this particular instance the spike is provided with a head 4 and the part 2 is bent around the same and 110

has two downwardly extending ends 5 between which is held the lever or plate S, or P.

A spring 6 is wound around the rock-shaft M, Fig. 3, one end being secured in some part of the device as for instance in the plate J to which it is adjacent, while the other end is secured in the rock shaft as for instance by extending it through the same.

- 10 The tendency of the spring is to maintain the parts in the position shown in Fig. 3 with the spikes W projecting above the upper surfaces of the bars in position to receive the sack. In securing the sack in place to be filled its edges are hooked upon the four spikes W in such a position that its mouth is spread very wide so that the contents of a scoop or shovel may be readily placed in it. When the proper weight is shown, or when
- 20 it is desired to remove the sack the lever T of the lever S is depressed and this action causes all the spikes to be simultaneously drawn downward into the tubes V so that the sack is at once released, the spring V returning the spikes to their normal or extended position ready for the reception of another sack.

It will be understood that by the arrangement described as to the nuts N O of the rock shaft M, that both of the levers P, *i. e.* at opposite sides, will be operated simultaneously.

I desire to state that I do not confine myself to the exact arrangement as to details shown and described since changes may be made that will lie within the meaning of the invention but it may be seen that the device is simple and effective and will hold a sack while being filled and whose contents

may be weighed while being filled thus saving considerable annoyance.

My device is distinguished from others of its class by its simplicity of structure and few parts and in the details of its construction.

45

Having described my invention, I claim:

1. In a sack holding device, in combination, a frame having an open side to receive a sack, a rock shaft extending between two of the frame portions at the back, a bell-crank-lever at each end of said shaft, a pair of bell-crank-levers pivoted to the frame, one at each side, and spaced from those of the shaft, a link connecting each bell-crank-lever of the pair with one of the levers of the shaft, and a member carried by each of the said levers adapted to hold the edges of the sack.

2. In a sack holding device, in combination, a frame having an open side to receive a sack, a rock-shaft extending between two of the frame portions at the back, a bell-crank-lever at each end of said shaft, a pair of bell-crank-levers pivoted to the frame, one at each side, and spaced from those of the shaft, a link connecting one of the bell-crank-levers of the pair with one of the levers of the shaft, a member carried by each lever adapted to hold the edges of the sack, and means to resiliently hold all the members in position to receive the sack.

In testimony whereof I affix my signature, in presence of two witnesses.

NICHOLAS MARIE.
